UNDERPANTS OR SHORTS

Allan James, Melbourne, Victoria, Australia

Application August 6, 1942, Serial No. 453,857

In Australia August 16, 1941

3 Claims.

(CL 2-236)

This invention relates to improvements in men's underpants or shorts of the kind which have elastic means incorporated in the waist to make the garment self-supporting on the wearer.

Usually garments of this kind have a strip of elastic webbing sewn around the waist or have gussets or inserts of elastic fabric sewn into the sides.

With such garments, it is found that the elastic material soon perishes or loses its elasticity due mainly to the frequent laundering these garments undergo. The elastic thus becomes non-effective in supporting the garment on the wearer and the garment becomes practically unwearable although the main material is quite good and capable of further wear.

The present invention overcomes this disadvantage and it consists in providing removable elastic bands which are attached to the waist portion of the garment by releasable attachment means. These bands thus can be quickly and conveniently removed from the garment and replaced by new bands when they become perished or stretched beyond effective use, thereby maintaining the garment self-supporting so that it can be continued to be worn.

Two relatively short elastic bands are preferably used and are arranged one on each side of the garment in positions above the wearer's hips. Such arrangement is found to be most effective as the bands by fitting over the wearer's hips provide ideal support with comfort and avoid concentrated tension or strain across the wearer's abdomen and back.

The elastic bands may be enclosed or partly enclosed in a hem or pocket at the waist portion of the garment with their ends extending out through slits or openings therein to engage the releasable attachment means. Alternatively, they may be externally attached to the garment and exposed to view.

Buttons co-operating with button-holes or slits form very suitable releasable attachment means for the elastic bands, but releasable clasps, clips or other means may be used.

The portions of the waistband across which the elastic bands extend are preferably formed of stretchable material such as the usual knitted cotton fabric from which the main portion of the garment is made so as to facilitate free gathering of the material under the tension of the elastic bands and comfortable stretching during wear. The remaining front and back portions of the waistband are preferably formed of fabric which is substantially non-stretchable.

Referring to the accompanying drawing which illustrates the preferred form of the invention—

Fig. 1 is a front view of a pair of men's underpants fitted with the replaceable elastic bands according to the invention.

Fig. 2 is a view of the garment from the side.

Fig. 3 is a view on an enlarged scale of one of the elastic bands.

As shown in these views, the two removable elastic bands 1 are arranged at the side portions 2 of the garment to lie just above the wearer's hips. The bands are enclosed in a hem with their ends 4 extending out through slits or openings 5.

The projecting ends 4 of the elastic bands are formed with holes 6 or the equivalent to engage buttons 7 sewn to the garment preferably adjacent to the slits 5.

The elastic bands may have only one hole 6 at each end or may have a plurality of holes as shown in Fig. 3 to provide for adjustment to suit the wearer.

In the manufacture of the garment, the main portion 8 is made from the usual stretchable material such as knitted cotton fabric. This fabric is extended upwards at 9 at the sides of the garment and formed into the hems 3 which enclose the elastic bands 1.

The front and back portions 10 and 11 of the waist are formed from folded pieces of preferably woven material which is relatively non-stretchable. The extended parts 9 are sewn to the ends of the portions 10 and 11 along the seams 12 and the slits 5 are formed in the said portions 10 and 11 preferably close to the seams 12.

The two elastic bands tend to gather the side portions 9 of the garment adjacent to the wearer's hips as shown in Fig. 1 and so impart sufficient elasticity to the waist portion of the garment to make the garment self-supporting on the wearer.

The upward extension of the material 8 to form the portions 9 provides stretchable fabric at the parts where the elastic bands 1 are positioned and so permits free gathering of the material under the tension of said bands and comfortable stretching of the waist of the garment during wear. The non-stretchable fabric portions 10 and 11 ensure close and neat fitting of the garment at the front and back and also provide stronger support for the buttons 7 than would be the case if they were sewn to the stretchable fabric 8.

55. The elastic bands can be very easily removed

when they become perished or have lost their elasticity by releasing the button fastenings and replaced by new bands, thus enabling the garment to be worn for its full life.

If desired, the elastic bands may be removed from the garment before the latter is laundered and replaced afterwards, thus increasing the life of the elastic bands. Ordinarily, however, the garment would be laundered in the usual way without removing the bands and the bands replaced only when perished or worn out.

The elastic bands are preferably made from rubber sheet or strip but elastic webbing or other elastic material is also suitable. The holes 6 formed in the ends of the bands to receive the buttons, may be suitably reinforced with fabric or other attachments to prevent tearing of the rubber about said holes. If a fabric reinforcement is used it may be adhesively attached to or incorporated in the rubber during manufacture or sewn thereto. In the latter case, the stitching may be arranged longitudinally of the band and not transversely to avoid weakening of the band.

In some cases, cloth or like tabs may be attached to the ends of the elastic bands and the button-holes 6 formed in said tabs.

In lieu of buttons and button-holes, other forms of fasteners may be used. Grip fasteners or clasps which will releasably grasp the ends of the elastic bands are suitable.

In some cases the elastic bands, instead of being partly enclosed in the hems 3, may be fitted externally to the garment across the portions 9, in which case the hems or pockets 3 may be dispensed with.

Other modifications may be made within the ambit of the invention.

What I claim is:

1. Underpants or shorts having a body of stretchable fabric a waistband consisting of completely independent front and rear portions of substantially non-stretchable fabric and two side

portions of stretchable fabric positioned over the wearer's hips, the side portions of stretchable fabric being formed by exposed portions of the body fabric, two removable elastic bands extending across said side portions of stretchable fabric, and means on the portions of non-stretchable fabric for removably securing the ends of said elastic bands in operative position relative to the portions of stretchable fabric.

10 2. Underpants or shorts having a body of stretchable fabric a waistband consisting of completely independent front and rear portions of substantially non-stretchable fabric and two side portions of stretchable fabric positioned over the wearer's hips, the side portions of stretchable fabric being formed by exposed portions of the body fabric, hems formed in said side portions of stretchable fabric, two removable elastic bands enclosed in said hems and having their ends extending out over the portions of non-stretchable fabric, and buttons on said portions of non-stretchable fabric to engage buttonholes in the ends of the elastic bands and removably secure said bands.

15 3. Underpants or shorts having a body of stretchable fabric a waistband consisting of completely independent front and rear portions of substantially non-stretchable fabric and two side portions of stretchable fabric positioned over the wearer's hips, the side portions of stretchable fabric being formed by exposed portions of the body fabric, hems formed in said side portions of stretchable fabric, two removable elastic bands extending through said hems, slits in the portions 20 30 of non-stretchable fabric through which the ends of the elastic bands pass out, and buttons on the portions of non-stretchable fabric adjacent to said slits to engage buttonholes in the ends of the elastic bands and removably secure said bands.

ALLAN JAMES.
